(57) **CLAIM**

We claim the ornamental design for a collapsible high back car booster seat, as shown and described.

DESCRIPTION

FIG. 1 is a front perspective view of the inventive collapsible high back car booster seat in the open position.

FIG. 2 is a front view of the collapsible high back car booster seat in the open position.

FIG. 3 is a rear view of the collapsible high back car booster seat in the open position.

FIG. 4 is a right side view of the collapsible high back car booster seat in the open position.

FIG. 5 is a left side view of the collapsible high back car booster seat in the open position.

FIG. 6 is a top view of the collapsible high back car booster seat in the open position.

FIG. 7 is a bottom view of the collapsible high back car booster seat in the open position.

FIG. 8 is a front perspective view of the collapsible high back car booster seat in the fully extended position.

FIG. 9 is a front view of the collapsible high back car booster seat in the fully extended position.

FIG. 10 is a rear view of the collapsible high back car booster seat in the fully extended position.

FIG. 11 is a right side view of the collapsible high back car booster seat in the fully extended position.

FIG. 12 is a left side view of the collapsible high back car booster seat in the fully extended position.

FIG. 13 is a top view of the collapsible high back car booster seat in the fully extended position.

FIG. 14 is a bottom view of the collapsible high back car booster seat in the fully extended position.

FIG. 15 is a front perspective view of the collapsible high back car booster seat in the fully folded position.

FIG. 16 is a front view of the collapsible high back car booster seat in the fully folded position.

FIG. 17 is a rear view of the collapsible high back car booster seat in the fully folded position.

FIG. 18 is a left side view of the collapsible high back car booster seat in the fully folded position.

FIG. 19 is a right side view of the collapsible high back car booster seat in the fully folded position.

FIG. 20 is a top view of the collapsible high back car booster seat in the fully folded position; and,

FIG. 21 is a bottom view of the collapsible high back car booster seat in the fully folded position.
